US0D1104813S

(12) **United States Design Patent** (10) Patent No.: **US D1,104,813 S**
(45) Date of Patent: ** Dec. 9, 2025

(54) **SECURITY TAG**

(71) Applicant: **Sensormatic Electronics, LLC**, Boca Raton, FL (US)

(72) Inventors: **Channing Everett Miller**, Fort Lauderdale, FL (US); **Sergio M. Perez**, Lake Worth, FL (US)

(73) Assignee: **Sensormatic Electronics, LLC**, Boca Raton, FL (US)

(**) Term: **15 Years**

(21) Appl. No.: **29/909,900**

(22) Filed: **Aug. 11, 2023**

Related U.S. Application Data

(63) Continuation of application No. 29/809,092, filed on Sep. 24, 2021, now Pat. No. Des. 997,758, which is

(57) **CLAIM**

The ornamental design for a security tag as shown and described.

DESCRIPTION

FIG. 1 is a front left perspective view of a security tag showing our new design;

FIG. 2 is a front right perspective view of the design shown in FIG. 1;

FIG. 3 is a left side view of the design shown in FIG. 1;

FIG. 4 is a right side view of the design shown in FIG. 1;

FIG. 5 is a front view of the design shown in FIG. 1;

FIG. 6 is a rear view of the design shown in FIG. 1;

FIG. 7 is a top plan view of the design shown in FIG. 1;

FIG. 8 is a bottom plan view of the design shown in FIG. 1;

FIG. 9 is a rear right perspective view of the design shown in FIG. 1; and,

FIG. 10 is a rear left perspective view of the design shown in FIG. 1.

The broken lines shown in the figures are included for the purpose of illustrating portions of the security tag and form no part of the claimed design.

1 Claim, 10 Drawing Sheets

Related U.S. Application Data

a continuation of application No. 29/755,784, filed on Oct. 22, 2020, now Pat. No. Des. 988,895, which is a continuation of application No. 29/755,783, filed on Oct. 22, 2020, now Pat. No. Des. 988,894, which is a continuation of application No. 29/639,063, filed on Mar. 2, 2018, now Pat. No. Des. 915,918.
